CLAIM

The ornamental design for a bassinet for baby carriage, as shown and described.

DESCRIPTION

1. Part of baby carriage
- 1.1 is a front, top, and left side perspective view of a bassinet for baby carriage showing our new design;
- 1.2 is a front elevation view thereof;
- 1.3 is a rear elevation view thereof;
- 1.4 is a left side elevation view thereof;

(Continued)

1.5 is a right side elevation view thereof;

1.6 is a top plan view thereof; and

1.7 is a bottom plan view thereof.

The broken lines in the drawings depict portions of the bassinet for baby carriage that form no part of the claim.
